UNITED STATES PATENT OFFICE.

BRADLEY S. BRYANT, OF HANSON, MASSACHUSETTS.

IMPROVEMENT IN INSOLES.

Specification forming part of Letters Patent No. 123,675, dated February 13, 1872.

To all to whom these presents shall come:

Be it known that I, BRADLEY S. BRYANT, of Hanson, in the county of Plymouth and State of Massachusetts, have invented a new and useful Improved Inner Sole to Boots and Shoes; and that the following is a full, clear, and exact description of the same, reference being had to the accompanying plate of drawing.

This improved inner sole is composed of a blank, having the outline of a person's foot, that is made from paper or other suitable sheet material and has either one or both of its surfaces coated or covered with a flock of wool, silk, cotton, hair, or of other suitable material, which is caused to adhere by cements or other suitable adhesive material—preferably a water or sweat-proof cement—previously applied to said surfaces of inner-sole blank.

In the accompanying plate of drawing my improved inner sole is illustrated, Figure 1 being a plan view of the same, and Fig. 2 a central section in the direction of its length.

A in the drawing represents my improved inner sole. This inner sole A, in the present instance, is shown as composed of a blank, *a*, that is cut from a sheet of paper in the outline of a person's foot, and its surfaces *b* covered or coated with a flock of wool, silk, cotton, hair, or other suitable material, represented in the drawing by a heavy black line each side of the blank *a*. This coating of flock is secured to the blank *a* by preparing its surfaces *b* with a cement or other suitable adhesive material—preferably, a water or sweat-proof cement—and then throwing thereon the flock, the cement, as it dries or hardens, causing the flock to firmly and rigidly adhere.

To facilitate the drying of the cement a heated smoothing-iron may be passed over the flocked surfaces of the blank, it serving also to lay and press the flock more evenly upon the blank and to give a smoother flock finish; and these last results may be accomplished even with a cold smoothing-iron.

An inner sole made as above described is in many respects desirable, among which may

be mentioned that, while costing but little compared with inner soles as heretofore made, it is serviceable, durable, and neat; and with a proper quality of stock for the blank, also, can be made as well very light.

It is preferable to flock both surfaces of the inner-sole blank; but one only may be flocked and the other left exposed.

In the drawing the inner sole is shown as made with perforations, *c*; these are for the purpose of ventilation, and in the manufacture of the inner sole I shall probably make perforations in the blank; but I do not intend to limit my invention to the use of them. The perforations may be made either before or after flocking; and if before, and by flocking over them they are made rather small, it is obvious they will be shielded from view by the flock, while, at the same time, ventilation can take place.

It may be well to here observe that there are many and various well-known cements which may be used to secure the flock to the blank; but those cements are preferable which, while fastening the flock, will not penetrate the paper or other sheet material of which the blank is to be made sufficient to destroy its character and firmness.

Although I have herein described my inner sole as made of a blank from a sheet of paper, other sheet materials, such as card, straw, paste, or leather-board, or buckram, or other woven sheet material, or even leather, may be used for the body of the sole, the flocking of the same giving a finish thereto and producing a desirable and complete inner sole.

Having thus described my invention, what I claim, and desire to secure by Letters Patent, is—

As a new article of manufacture, an inner sole, for use in boots and shoes, covered with flock, substantially as herein described.

B. S. BRYANT.
